CLAIM

The ornamental design for a sandal, as shown and described.

DESCRIPTION

1. Sandal
- 1.1 : Perspective
- 1.2 : Front
- 1.3 : Back
- 1.4 : Right
- 1.5 : Left
- 1.6 : Top
- 1.7 : Bottom

The present design relates to a sandal comprising a sole with a heel, a front strap extending from the forward portion of the sole and an ankle strap connected to the rear portion of the sole by two almost vertical strips; both the front strap and the ankle strap are provided with a respective adjustment buckle.

1 Claim, 7 Drawing Sheets
